UNITED STATES PATENT OFFICE.

THOMAS G. STODDARD, OF BOSTON, MASSACHUSETTS, ASSIGNOR TO THE AMERICAN POSTAL MACHINES COMPANY, OF BOSTON, MASSACHUSETTS, A CORPORATION OF MAINE.

MAIL-MARKING MACHINE.

1,152,347.

Specification of Letters Patent.

Patented Aug. 31, 1915.

Application filed December 26, 1912. Serial No. 738,528.

To all whom it may concern:

Be it known that I, THOMAS G. STODDARD, a citizen of the United States, residing at Boston, in the county of Suffolk and State 5 of Massachusetts, have invented certain new and useful Improvements in Mail-Marking Machines; and I do hereby declare the following to be a full, clear, and exact description of the invention, such as will enable 10 others skilled in the art to which it appertains to make and use the same.

The invention relates to mail marking machines, and more particularly to mechanism for controlling the operation of the die carrying roll.

The object of the invention is to provide novel and improved devices through which the rotation of the die carrying roll may be controlled by the mail matter passing 20 through the machine, and to this end the invention comprises the features of construction and combinations of parts herein-after described and referred to in the claims.

The invention will be readily understood 25 from an inspection of the accompanying drawings and the following detailed description of the mechanism illustrated therein.

In the drawings, Figure 1 is a plan view 30 showing a mail marking machine embodying the invention in its preferred form; Fig. 2 is a vertical sectional view through the die carrying roll; Fig. 3 is a detail view of the latches for controlling the rotation of the 35 die carrying roll; and Fig. 4 is a detail view of the sleeve on which the stops for the die carrying roll are formed.

In the machine illustrated, the letters or other pieces of mail matter are fed in succession between the die carrying roll 1 and the impression roll 2 by feed rolls 3, and are delivered from the marking rolls to a stacking device 4 by the delivery rolls 5. The die carrying roll is provided with the usual stamp canceling and post marking die 6, and is secured upon a sleeve 7 mounted to turn freely upon a stationary shaft 8. The hub of the sleeve 7 is surrounded by a rotary driving sleeve 9, the upper end of which carries a friction ring 10 adapted to engage a flange 11 on the sleeve 7 and to transmit motion to the sleeve. The die carrying roll is normally held against rotation and is released and stopped by devices operated by

the letters passing between the feed rolls 3. 55 In the construction shown, the devices for controlling the rotation of the die carrying roll comprise two stops 12 and 13 formed on a collar 14 which is secured to the roll carrying sleeve 7, so that the stops move with the 60 marking die. The stops are arranged in different planes, the stop 12 being in a higher plane than the stop 13. The stops coöperate with two latches 15 and 16, which are formed on a pivoted arm 17 and are so 65 arranged that movement of one latch out of the path of the coöperating stop brings the other latch into the path of its coöperating stop. The latches are rendered alternately and successively active and inactive by a 70 finger 18 carried by the arm 17 and arranged to extend across the letter path between the feed rolls 3. The controlling finger 18 and the latches are held normally in the position indicated in Fig. 1 by a spring 19, one end 75 of which is connected to the arm 17, and the other end of which is connected to the base plate 20 of the machine.

When no letter is passing through the machine, the parts are in the position indicated 80 in Fig. 1, with the controlling finger 18 extending across the letter path, and with the stop 12 in engagement with the latch 15. When the forward end of a letter strikes the finger 18, it swings the arm 17 about its 85 pivot, thus disengaging the latch 15 from the stop 12, so that the marking die is released and is rotated by the frictional engagement of the driving sleeve 9 with the die carrying sleeve 7. The movement of the 90 arm 17 which disengages the latch 15 from the stop 12 also brings the latch 16 into the path of the stop 13, so that the rotation of the marking die is arrested by the engagement of the stop 13 with the latch 16 after 95 it has nearly completed a revolution. The parts are held in this position by the engagement of the letter with the finger 18 until the rear end of the letter passes beyond the finger, when the spring 19 swings the arm 100 17 back into the position indicated in Fig. 1. This returns the finger 18 into position across the letter path, disengages the latch 16 from the stop 13, and brings the latch 15 into the path of the stop 12. When the 150 latch 16 is disengaged from the stop 13 the die carrying roll completes its revolution, bringing the stop 12 into engagement with

the latch 15, so that the parts are reset in position for properly marking the succeeding letter.

While it is preferred to employ the specific construction and arrangement of parts shown and described, it will be understood that this construction and arrangement are not essential, and may be varied and modified without departing from the broader 10 features of the invention.

Having explained the nature and object of the invention, and specifically described one form of machine in which it may be embodied, what is claimed is:—

15 1. A mail marking machine, having, in combination, a rotary marking die, two stops connected to rotate therewith, an arm provided with two coöperating latches, and means controlled by the letter for moving 20 the arm to render the latches alternately and successively active and inactive.

25 2. A mail marking machine, having, in combination, a rotary marking die, two latches which are alternately active, means 30 connected with the die to coöperate with the latches in stopping and releasing the die, and means operating when engaged by the letter to render one latch inactive and the other active, and operating when released by 35 the letter to render the latter latch inactive and the former again active.

35 3. A mail marking machine, having, in combination, a rotary marking die, two stops connected to rotate therewith, two coöperating latches, and a controlling finger ar-

ranged across the letter path and connected to shift the latches alternately into and out of the paths of the corresponding stops by its movement back and forth across the letter path.

4. A mail marking machine, having, in combination, a rotary marking die, two stops connected to rotate therewith and arranged in different planes, a pivoted arm provided with latches arranged to be moved alternately into and out of the paths of the stops, and a finger carried by the arm and extending across the letter path.

5. A mail marking machine, having, in combination, a rotary marking die, two 50 latches for alternately stopping the roll, a letter engaging device connected to render one latch inactive and the other active when engaged by the letter, and to render the latter latch inactive and the former again active when the letter has passed.

6. A mail marking machine, having, in combination, a rotary marking die, a latch for holding the die in normal position, a finger extending across the letter path and connected to move the latch out of active position when moved out of the letter path and into active position when returned to initial position, and a second latch connected to be moved into and out of active position 65 in alternation with the first latch.

THOMAS G. STODDARD.
